FOLDING CONCRETE FORM

Walter C. Nicolls, San Jose, Calif.

Application October 4, 1946, Serial No. 701,229

5 Claims. (Cl. 25—131)

1

My present invention relates generally to concrete structures of the monolithic type, and more particularly to an improved foldable concrete-form for use in erecting solid, or hollow, concrete walls for buildings or other structures.

The primary object of the invention is the provision of a sectional mold-form for the plastic concrete that may easily and quickly be erected with a minimum expenditure of time and labor; with equal facility the forms may be dismantled for repeated use in constructing or pouring successive courses in a wall; and finally the forms may be detached from the completed wall, and folded into compact shape for storage and transportation purposes.

In carrying out my invention the sections, which make up the form for a course, each includes a pair of hinged panels consisting of a minimum number of component parts that may readily be manufactured and assembled, and the panels of a section are equipped with co-acting parts for bracing and supporting the mold when in place.

The invention consists in certain novel combinations and arrangements of parts as will hereinafter be described and set forth in the appended claims.

In the accompanying drawings I have illustrated one complete example of the physical embodiment of my invention wherein the parts are combined and arranged in accord with one mode I have devised for the practical application of the principles of my invention; but it will be understood that changes and alterations may be made in these exemplifying drawings and mechanical structures within the scope of my claims without departing from the principles of the invention.

Figure 1 is a plan view showing the concrete mold in position for constructing an angular wall.

Figure 2 is an exterior view in elevation of one of the mold-sections or forms, the hinged panels of the section being braced and locked together for use.

Figure 3 is a view in elevation showing a modified shape that may be given to the hinged panels, for auxiliary use.

Figure 4 is an enlarged vertical sectional view at line 4—4 of Fig. 1, showing the upper panel of a section braced and locked in position and supported by the lower panel.

Figure 5 is a detail sectional view at line 5—5 of Figure 1 illustrating the hinge arrangement between the pair of panels of a section.

Figure 6 is a view in side elevation of a con-

2

ventional core used in the construction of a hollow monolithic wall.

Figure 7 is a transverse vertical sectional view of the core at line 7—7 of Fig. 6, with the core expanded.

Figure 8 is a view similar to Fig. 7, but with the core contracted.

Figure 9 is a top plan view of the collapsible slit core, broken away at one end to illustrate 10 the overlapping joint in its walls.

In the assembly view Fig. 1 the inner form A and the outer form B are made up of a number of the sections, as are also the corner structures C and D, and the forms as unitary structures 15 consist of these sections that are interconnected and interlocked to provide a rigid mold for the plastic concrete. The sections include horizontally hinged panels which are erected, end to end, in horizontal planes to form courses, and the lower 20 tier of panels in a course provide the mold for the first course of concrete. While this first course is being poured the upper horizontal tier of panels is preferably folded downwardly and away from the mold; and after the first course is set, 25 the upper tier of panels is infolded to upright position, braced and locked from the lower tier of panels, to provide the mold for the second pouring of plastic concrete.

For pouring successive courses of the plastic 30 concrete, the sectional forms are dismantled and elevated, and by this combination and arrangement of parts in the unitary molds, each section of a mold becomes a self-supporting unit in a mold form.

35 One of the standardized hinged sections is illustrated in detail in Figs. 2, 4, and 5, where a pair of oblong or rectangular angle iron frames 1 and 2 are each provided with a smooth, rust-proof, metal face plate, as 3 and 4, preferably 40 welded to the frame structures.

The lower edge 5, and the right hand end 6 of each plate of a panel projects beyond the frame to form flanges or tongues that overlap adjoining panels; and the upper edge 7 and the left 45 end 8 of each face plate terminates short of the frame to form recesses or grooves for the reception of the tongues. In this manner interlocking joints are provided between adjoining panels and sections, and leaf-proof connections are made 50 between the panels to insure smooth faces for the concrete wall.

The upper and lower panels are each provided with exterior, vertical channel-braces 9, welded to and uniting the upper and lower bars of the 55 frame and the face plates to form a rigid struc-

ture, and to provide supports for movable parts of the panels.

For horizontally hinging the panels of a section two pairs of the vertically aligned braces 9 near the ends of the section are utilized, and a vertical or upright hinge-bar 10, which spans the adjoining edges of the panels, is pivoted at its ends by two links 11, 11, to the channel plates or braces 9.

This arrangement of the hinges provides for a wide swing of the upper panel away from the lower when the panels are folded, but as seen in Fig. 5, the hinges, together with the tongue and groove connections at adjoining edges of the panels, tend to rigidly hold the panels in alignment to insure a plumb wall.

The tiers of panels of the inner form A and of the outer form B are united by means of tie bolts 12, each having an exterior crank handle 13, a fixed exterior collar 14 and nut 15 threaded on the end of the bolt. The bolt is passed through holes in the upper part of complementary outer and inner panels of the mold, with the collar bearing against the outer face of a frame bar, and the nut is threaded on the end of the bolt exterior of a frame rail of an inner panel. The outer and inner forms of the mold are thus spaced apart, and clamped together to form the desired thickness for the concrete wall.

For alining and plumbing the upper panel, and bracing it from the lower panel, each panel is equipped with a pair of spaced arms 16, pivoted at 17 on one of the vertical channel braces 9 at the upper edge of a panel, and this arm, at its free end terminates in a socket head or slotted U-shaped head 18 turned at an angle to the arm as indicated.

In molding position, the upper panel is supported from the head 18 of the lower panel by means of a diagonally arranged bolt 19 hinged on the pivot pin 17 of the arm of the upper panel, with the otherwise free end of the bolt 19 located in the socket head of the horizontal arm, and a pair of lock nuts 20, 21 at opposite faces of the head are employed to lock the adjusted bolt and horizontal arm in rigid relation with the panels.

In addition to the bracing action of the bolt, diagonal links 22 are hinged at 23 to the lower part of a panel, and detachably bolted or pinned at 24 to the horizontal arm 16 to insure an X-shaped frame for supporting the upper panel in proper position.

The hinged panels, the pivoted and hinged arms, bolts, and braces, as will be apparent may be manipulated with ease in folding and unfolding these parts for use in erecting the outer and inner forms, as well as for compacting the sections in small area for storage or transportation purposes.

While I have illustrated the panels generally of oblong shape, it will be understood that other shapes may be employed, as for instance, a square shaped panel 25 in Fig. 3 may be utilized as desired.

For pouring hollow or cellular walls of concrete, collapsible cores may be employed, one of which is indicated in Figs. 6 through 9, where the open bottom split core includes two side walls 26 and 27 having split tops 28 and 29 that are hinged together at 30.

The walls are fashioned with overlapping ends 31 and the free ends of the core-halves may be projected and retracted by means of a pair of toggle devices, each device including a push and pull rod 32 which passes through a hole in the top of the cover. The operating rod is provided with an exterior head or handle 33, and the lower end of the rod within the core is equipped with two links 34, 34, hinged at 35 to the walls of the split core.

The split core may be retracted for insertion and withdrawal from the concrete wall, and it may be projected or expanded to proper shape for the formation of voids or cavities in the completed wall.

Having thus fully described my invention, what I claim as new and desire to secure by Letters Patent is:

1. In a concrete mold-section, the combination with a pair of horizontally hinged panels, of a horizontal arm and integral head mounted on the lower panel, a diagonally arranged bolt mounted on the upper panel, and co-acting means on the head and bolt for holding the panels in vertical alignment.
2. In a concrete mold-section, the combination with a pair of longitudinally hinged panels, of a horizontal arm and integral head pivotally mounted on the lower panel, a bolt pivotally mounted on the upper panel, and a pair of lock nuts for clamping the head and bolt.
3. In a concrete mold-section, the combination with a pair of horizontally hinged panels having face plates, said face plates having a tongue and groove connection at adjoining edges, of a horizontal arm and head pivotally mounted on the lower panel, a diagonally arranged bolt pivoted on the upper panel, and lock nuts on the bolt for coaction with said head.
4. In a concrete mold section, the combination with a pair of hinged panels each including a rectangular face plate, each of said face plates having a right-angle tongue and a right-angle groove adapted to form overlapping joints, of a horizontal arm and head pivotally mounted on the lower panel, a diagonally arranged bolt pivoted on the upper panel, and lock nuts on the bolt for coaction with said head.

5. In a concrete mold-section the combination with a pair of panels having a tongue and groove joint between adjoining edges, of a pair of hinges each including a vertical hinge bar spanning said edges, pivoted links on said bar connected to the respective panels, and means mounted on the respective panels for co-action in retaining them in alignment.

WALTER C. NICCOLLS.
